UNITED STATES PATENT OFFICE.

JOHN McLEAN, OF CAMDEN, ALABAMA.

COMBINATION-SQUARE.

No. 839,182.

Specification of Letters Patent.

Patented Dec. 25, 1906.

Application filed July 21, 1906. Serial No. 327,204.

To all whom it may concern:

Be it known that I, JOHN McLEAN, a citizen of the United States, residing at Camden, in the county of Wilcox and State of Alabama, have invented a new and useful Combination-Square, of which the following is a specification.

This invention relates to combination-squares of the type disclosed in United States Patent No. 535,717, granted to me March 12, 1895.

The object of the present invention is to improve and simplify the construction of the combination-square forming the subject-matter of the above patent.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings, forming part of this specification, Figure 1 is a side elevation of a combination-square constructed in accordance with the invention. Fig. 2 is an enlarged detail view showing the upper end of the stock. Fig. 3 is a transverse section through the sight-opening.

Like reference-numerals indicate corresponding parts in the different figures of the drawings.

The improved combination-square of this invention comprises a stock 1, which is formed adjacent its upper end with a circular sight-opening 2. The sight-opening 2 serves to produce at the upper end of the stock 1 a web 3, across which extends an index-line 4.

The reference-numeral 5 indicates the pivot-point of a main blade 6, which is connected with the lower end of the stock 1, as shown. The main blade 6 is formed with a slot 7, which is concentric with the pivot-point 5 and is adapted to receive the shank of an adjusting-screw 8, which extends through the stock 1, as shown. By loosening the adjusting-screw 8 the main blade 6 can be moved pivotally upon the stock 1 and clamped in adjusted position by tightening the adjusting-screw 8. Above the concentric slot 7 the main blade 6 is provided with an ordinary scale or graduation 9, which is

concentric to the pivot-point 5 and is adapted to be read at the lower end of the index-line 4 through the sight-opening 2 when the main blade is moved pivotally upon the stock. Above the ordinary scale 9 the main blade 6 is provided with what I shall term a "rafter-scale" 10, which contains certain marks or graduations by means of which the main blade can be readily adjusted upon the stock and adapted for the proper marking of rafters and the like. The rafter-scale 10 is concentric to the pivot-point 5 and is adapted to be read at the upper end of the index-line 4, as will be apparent. The provision of the sight-opening 2, which forms the web 3, adapted to receive the index-line 4, constitutes a valuable improvement over the construction shown in my former patent, as the index-line can be inexpensively placed upon the web and when so placed will not be in danger of defacement or removal, whereas the pointer contained in my former construction was liable to become bent or displaced if the tool should receive rough treatment.

The main blade 6 is provided along its outer edge 11 and upper edge 12 with what I shall term a "polygon-scale," in that by means of the stock 1 and main blade 6, together with the polygon-scale, the different radial lines of an octagon or other geometrical figure can be readily calculated.

The main blade 6 is provided with an integral extension-blade 14, which projects through a suitable slot in the stock 1 and is adapted to be used in conjunction with said stock for securing different angles. The blade 14 preferably is provided with a series of perforations 15, adapted to receive a nail or other pointed instrument to act as a center or pivot, so that when a pencil-point is passed through the pencil-opening 16 in the stock 1 the combination-square can be used for drawing a circle.

From the foregoing description it is believed that the different ways in which the combination-tool can be used will be readily apparent to those skilled in the art.

The improved combination-square of this invention is strong, simple, durable, and inexpensive in construction, as well as thoroughly efficient in operation.

What is claimed is—

1. A combination-square comprising a stock having at its upper end a sight-opening forming a web, said web being provided

- with an index-line extending thereacross, one end of said index-line terminating at the upper end of the stock and the other end of said index-line terminating at the upper part 5 of the sight-opening, a main blade pivotally connected with the lower end of the stock and having a slot concentric to the pivot-point of the blade, said main blade being provided with an ordinary scale concentric 10 to its pivot-point and adapted to be read at one end of said index-line, a rafter-scale on the blade concentric to its pivot-point and adapted to be read at the other end of said index-line, an extension-blade connected 15 with the upper portion of said main blade and extending through a slot in said stock, and an adjusting-screw extending through the stock and through the concentric slot in 20 said main blade.
2. A combination-square comprising a stock having adjacent its upper end a sight-opening forming a web having an index-line extending thereacross, one end of said index-line terminating at the upper end of the stock and the other end of said line terminat- 25
- ing at the upper end of the sight-opening, a main blade pivotally connected with the lower end of the stock and having a slot concentric to the pivot point thereof, said blade being provided with an ordinary scale concentric to its pivot-point and adapted to be read through said sight-opening at one end of said index-line, a rafter-scale on the blade concentric to its pivot-point and adapted to be read at the other end of said index-line, 30 polygon-scales extending along the outer and upper edges of said main blade, an extension-blade connected with the upper portion of said main blade and extending through a slot in said stock, and an adjusting-screw 35 extending through the stock and through the concentric slot in said main blade.
- In testimony that I claim the foregoing as my own I have hereto affixed my signature in the presence of two witnesses.

JOHN McLEAN.
